UNITED STATES PATENT OFFICE.

OSWALD E. WINGER, OF FREEPORT, ILLINOIS, ASSIGNOR OF ONE-HALF TO
ELAM B. WINGER, OF SAME PLACE.

WINDMILL.

SPECIFICATION forming part of Letters Patent No. 293,836, dated February 19, 1884.

Application filed December 6, 1883. (No model.)

To all whom it may concern:

Be it known that I, OSWALD E. WINGER, a resident of Freeport, in the county of Stephenson and State of Illinois, have invented certain new and useful Improvements in Windmills; and I do hereby declare the following to be a full, clear, and exact description of the invention, such as will enable others skilled in the art to which it pertains to make and use 10 the same.

My invention relates to improvements in windmills of that class in which the power of the wind-wheel is applied to the rotation of a vertical power-transmitting shaft, and which 15 are known as "power-mills," as distinguished from pumping-mills.

The object of the invention is to prevent the reaction of the work on the vertical shaft from throwing the wind-wheel out of the wind; and 20 the invention is fully explained, described, and claimed in the following specification and shown in the accompanying drawings, in which--

Figure 1 is a side elevation of one form of mill embodying the invention; Fig. 2, a central vertical section of the same, the plane of section passing through the line $x'y'$, Fig. 3; Fig. 3, a plan of same, that part of the mill being removed which is above a horizontal 25 plane passing through the line $x'y$, Fig. 1; Fig. 3c 35 plane passing through the line $x''y''$, Fig. 4; and Fig. 6, a top view of the plates D C B, Fig. 4.

In the mill shown in Figs. 1, 2, and 3, A is a tower of ordinary form, and B an annular 40 plate formed with ratchet-teeth on its edge, and provided with integrally-formed projecting plates or arms a, which are bolted or otherwise fastened to the tower.

Within the ring B rotates freely the conical sleeve O, provided with a horizontal flange, C, which rests on the ring B, and also with a bearing, F, in which is journaled a horizontal shaft, G'', whose use is hereinafter explained, both the flange C and bearing F being formed 50 integrally with the sleeve O.

Within the sleeve O is a second conical sleeve, O', formed integrally with a horizontal plate, D, which rests on the flange C, and also with a bearing, E, in which is journaled the horizontal shaft G' of an ordinary wind-wheel, 55 I. The shafts G' G'' are in the same horizontal plane, and are connected by a universal-joint coupling, H, which insures their uniform rotation in their bearings, but permits their bearings to move independently about the vertical axis of the mill.

Within the sleeve O' rotates freely a vertical power-transmitting shaft, G, provided with a miter-gear, K, mounted on the upper end of the shaft, and engaging with a similar gear 65 mounted on the horizontal shaft G''. The contiguous faces of the plates B C D are provided with corresponding annular grooves, in which are anti-friction balls Q, which sustain the pressure between the parts. The lower end of the 70 sleeve O is journaled in a horizontal ring, N, attached to the tower by means of integrally-formed arms J. The casting F is provided with a boss, M, lying outside of and just above the plane of the ratchet-plate B, and to this 75 boss is pivoted a horizontally-swinging pawl, M', which engages with the ratchet. A spring, e, attached to the casting F, tends to preserve the engagement of the pawl and ratchet by pressing against the outer face of the pawl. 80

On the periphery of the plate D are two outwardly-projecting lugs, L L', arranged symmetrically with reference to the bearing E of the wind-wheel, and at such an angular distance apart that if the plate D be rotated 85 forty-five degrees in either direction from its position as shown in Fig. 3, one of the lugs L L' will strike the casting F. The lug L is provided at its outer and lower end with an arm, L'', lying just outside of the ratchet B, 90 and extending toward the pawl M', the position and length of the arm being such that when the plate D is rotated from left to right (or in the direction indicated by the arrow a, Fig. 3) the arm L'' passes under the casting F, 95 strikes the pawl M', and lifts it out of engagement with the ratchet just before the lug L strikes the casting F. The wind-wheel I rotates in the direction indicated by the arrow on the spider in Fig. 1, and the shaft G'' and 100

gear K' rotate in the same direction. The shaft G and gear K rotate in the direction indicated by the arrow on the gear in Fig. 1, and as soon as any resistance is offered to the 5 rotation of the vertical shaft the reaction tends to roll the gear K' about the gear K from left to right, or in the direction indicated by the arrow *a*, Fig. 3. This tendency is resisted, however, by the engagement of the pawl M' 10 and ratchet B, which renders the bearing F stationary, so far as any influence of the reaction of the vertical shaft is concerned. As the connection between the shafts G' G'' is a flexible joint, the bearing E swings freely 15 about the vertical axis of the mill under the influence of the wind alone, and unaffected by the shaft G'' or its bearing F. If, now, the bearing E swing forty-five degrees from left to right, as indicated by the arrow *a*, Fig. 3, 20 the arm L'' disengages the pawl M', the lug L strikes the casting F, and the two bearings E F swing together from left to right until the bearing E comes to rest in the line of the wind, when the pawl again engages with the ratchet 25 and the bearing F becomes again stationary. If, on the other hand, the bearing E swing from right to left, or in the opposite direction to that indicated by the arrow *a*, Fig. 3, when the lug L' strikes the bearing F the lug and 30 bearing move in the same direction, the pawl M' passing from one tooth to another of the ratchet, and offering no resistance except the force exerted by the spring *e*. Thus while the pawl and ratchet effectually prevent the 35 bearing F from changing its position under the influence of the reaction of the vertical shaft, they leave it free to swing about the vertical axis of the mill, whenever required to do so, by the motion of the bearing E of the 40 wind-wheel shaft.

In the mill shown in Figs. 4, 5, and 6, A is the tower, whose top is a plate, A', having a central circular opening, in which turns freely a turn-table, S, the adjacent faces of the plate 45 and turn-table being separated by anti-friction balls. The turn-table S has cast with it a bearing, E, in which is journaled the horizontal wind-wheel shaft G', and there is also formed integrally with the turn-table a central 50 web, b, Figs. 4, 5, from the lower side of which depends an integrally-formed hub, c. On the wind-wheel shaft G', at the center of the turn-table, is rigidly mounted a chain-pulley, f, whose use is hereinafter explained.

55 In the center of the tower, at such distance below the turn-table as is desired, is an annular ratchet-plate, B, provided with ears or flanges *a*, which are bolted to the timbers of the tower.

60 Within the plate B rotates freely a plate, C, from whose lower face depends the rigid frame V, in whose sides is journaled a horizontal shaft, d, Fig. 4.

On the shaft *d*, in the line of the vertical axis 65 of the mill, is mounted a chain-pulley, f', and a bevel-gear, K'', is mounted on the same shaft and engages with a second bevel-gear mounted

on a vertical power-transmitting shaft, G, which is journaled in the lower side of the frame V.

At one side of the plate C is a raised projecting lug, F, provided with a boss, M, to whose lower face is pivoted a horizontally-swinging pawl, M', engaging with the stationary ratchet B, the pawl being held in engagement with the ratchet by a spring, *e*, fastened 70 to the lug F. A vertical shaft, G'', rests and rotates freely in a socket at the center of the upper face of the plate C, the upper end of the shaft entering the hub *c*, heretofore referred to, and being rigidly held therein by a set-screw. A plate, D, consisting of an annular outer portion and a diametrical web, is rigidly fastened to the shaft G'', immediately above the plate C, the shaft passing through the center of the web, and the plate D, shaft G'', and 75 turn-table S, forming a single rigidly-united structure which rotates together. A chain-belt, R, passes around the chain-pulleys *f f'*, through the open spaces on either side of the web in the plate D, and through two holes in 80 the plate C, Fig. 6, and this chain-belt forms a flexible coupling between the shafts G' *d*, transmitting the motion of the shaft G' to the shaft *d*, and at the same time allowing the shaft *d* to rotate in a horizontal plane about a vertical axis, independently of the shaft G' within 85 the limits of torsion of the chain-belt.

To the periphery of the annular plate D are attached two lugs, L L', Fig. 6, the lug L being provided with an arm, L', extending 90 toward the pawl M'. The office of the lugs L L' and arm L' is precisely the same as that of the corresponding parts shown in Fig. 3. The rotation of the turn-table with the changes of direction of the wind brings these lugs L L' 95 against the lug F of the plate C. When the plate D moves in the direction indicated by the arrow *a'* on its face, the lug L' strikes the lug F, and the pawl slips over the successive teeth of the ratchet. When, on the other hand, the 100 plate D moves in the opposite direction, the arm L'' passes under the lug F, lifts the pawl M' out of engagement with the ratchet, and permits the lug F and plate C to yield to the pressure of the plate D.

105 It will readily be seen that the two forms of mill shown are identical in principle and operation. The shaft G' of the wind-wheel is the same in both mills, and the shaft G'' of the mill shown in Fig. 1 corresponds to the shaft 110 *d* of the mill shown in Fig. 4, the two horizontal shafts in each mill being connected by flexible connections, a universal-joint coupling being used in one case and a chain-belt in the other.

115 In both the mills shown the angular space between the lugs L L' is ninety degrees; but this angle may be decreased to any desired extent, its maximum limit, however, being the working range of the flexible connection.

120 No means for regulating the speed of the wind-wheel is shown in either form of mill; but any of the well-known devices for that purpose may be applied to either of them.

Having now described and explained my invention, what I claim as new, and desire to secure by Letters Patent, is—

1. In a windmill of the class described, the combination of two horizontal shafts journaled in independent bearings and connected by means adapted to insure their simultaneous rotation in their bearings, but to permit limited independent rotation of their bearings about the vertical axis of the mill, a wind-wheel mounted on one of said shafts, gearing connecting the other of said shafts with the vertical power-transmitting shaft of the mill, a pawl attached to the bearing of said last-named horizontal shaft and engaging with a ratchet attached to the tower of the mill, said pawl and ratchet being adapted, when in engagement, to prevent the rotation of said bearing in a direction opposite to the direction of rotation of the vertical power-transmitting shaft, and means attached to the bearing of the wind-wheel shaft, whereby the rotation of said bearing beyond its prescribed limit shall disengage said pawl and ratchet and cause the rotation of the bearing to which said pawl is attached, substantially as shown and described, and for the purpose set forth.
2. In a windmill of the class described, the combination of two horizontal shafts journaled in independent bearings and lying in the same horizontal plane, a universal-joint coupling connecting said shafts, a wind-wheel

mounted on one of said shafts, and a beveled gear mounted on the other and connecting it with the vertical power-transmitting shaft of the mill, a pawl attached to the bearing of said geared shaft and engaging with a stationary ratchet, and adapted to prevent the rotation of the bearing in the direction opposite to the direction of rotation of the vertical power-transmitting shaft, and means attached to the bearing of the wind-wheel shaft, whereby the rotation of said bearing, until it strikes the bearing to which said pawl is attached, disengages said pawl and ratchet, and causes the rotation of the bearing to which the pawl is attached, substantially as shown and described, and for the purpose set forth.

3. The combination of the bearings E F, ratchet-plate B, pawl M', attached to the bearing F and engaging with the ratchet-plate B, lugs L L', attached to the bearing E, and arm L'', formed integrally with the lug L, and adapted to disengage said pawl and ratchet, substantially as shown and described, and for the purpose set forth.

In testimony whereof I have signed this specification in the presence of two subscribing witnesses.

OSWALD E. WINGER.
